WASHING MACHINE

George W. Dunham, New Haven, Conn., assignor,
by mesne assignments, to Winchester Repeating Arms Company, New Haven, Conn., a corporation of Maryland

Application September 25, 1928, Serial No. 308,316

12 Claims.

(Cl. 68—23)

The invention relates in general to laundry machines and more particularly to washing machines of the centrifugal drying type.

According to one form of the invention the machine comprises essentially an outer container or tank having disposed therein a laundry receptacle which is adapted to oscillate for washing and to rotate for centrifugal drying. Suitable stabilizing devices are provided for supporting the container to take up effectively the out-of-balance forces set up by centrifugal drying and also to allow the machine to rest on an uneven surface without marring such surface or requiring fastening thereto.

Suitable gearing is provided, entirely enclosed in the gear box, for imparting the washing and drying motions to the machine. A peculiar washing motion is provided which not only washes efficiently, but serves to distribute evenly the clothes in the receptacle for smooth drying. Furthermore, suitable devices are provided for insuring complete segregation of the lubricating oil and water. Also, suitable bearings are provided, whereby comparatively long shafts are supported in but two bearings. A suitable clutch connection is provided so that the receptacle may be connected directly, without interposition of movable parts, to either the washing or drying motion imparting elements.

The machine may be of the small, portable type having the advantages of occupying but small space and operating efficiently on a small batch of laundry. This machine is conveniently used on a kitchen table or kitchen sink.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an elevation of the machine with parts in section;

Fig. 2 is a top plan view of the machine;

Fig. 3 is a plan section taken on the line 3—3 of Fig. 1;

Fig. 4 is a vertical section on line 4—4 of Fig. 2 through the clutch showing the receptacle at its lower or washing position;

Fig. 5 is a view similar to Fig. 4 showing the receptacle in its upper or drying position;

Fig. 6 is a plan section of the clutch taken on the line 6—6 of Fig. 5;

Fig. 7 is a vertical section taken through the gear box on the line 7—7 of Fig. 8;

Fig. 8 is a section taken on the line 8—8 of Fig. 7;

Fig. 9 is another vertical section taken through the gear box on the line 9—9 of Fig. 8;

Fig. 10 is another vertical section taken through the gear box on the line 10—10 of Fig. 8;

Fig. 11 is a vertical section taken through the tank illustrating the connection of the discharge hose;

Fig. 12 is a detail of the insulating connection for supporting the drive motor; and

Fig. 13 is a detail showing the manner of forming the holes in the receptacle.

In the following description and in the claims 20 parts will be identified by specific names for convenience, but they are intended to be as generic in their application to similar parts as the art will permit.

Like reference characters denote like parts in 25 the several figures of the drawings.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinafter defined and claimed.

Referring now to the drawings and, more particularly, to Figs. 1, 2 and 3, the laundry machine comprises in general a container or tank 1 having a pair of handles 2 and a cover 3 removably fitting on the top thereof. The tank is supported by a suitable supporting base ring 4 which encloses the driving motor 5 and gear box 6. Disposed within the tank is a foraminous receptacle 7 having agitator blades 8 therein. Suitable shafting and clutch devices are provided for selectively imparting to the receptacle 7 an oscillatory rotary motion for washing and a continuous rotary motion for drying. It will be understood that during washing the tank is filled to a suitable level, say, just below the top holes in the basket or receptacle 7, and for drying the water is drained out through the hose 9.

Referring now to the container or tank 1 and support therefor, the tank has a flat, conical bottom 10 having an opening in the center thereof in which is secured a fitting 11 (Fig. 9). This

fitting is provided with a plurality of studs 12 threaded at both ends which fit into holes in the bottom 10 of the tank. A suitable strengthening ring 13 surrounds the bottom opening and fits on the studs 12. Acorn nuts 14 hold the fitting 11 in position, gaskets 15 making a water tight joint.

16 Near one edge of the bottom 10 is a drain opening 16 to which is attached a pipe fitting 17 18. The rubber hose 9 slides over the fitting 17 and is provided with a ring clip 18 by which the hose is held in the position shown in Fig. 11, there being a member 19 secured to the side wall of the tank into which the clip is hooked.

18 The supporting ring 4 spreads slightly toward the bottom to increase the supporting area and is provided with an inwardly extending flange 20 at its upper end which is suitably fastened to the tank bottom 10 in any desirable manner, as by rivets. The lower end of the supporting ring 4 is provided with an annular, angular seat 22 in which are seated a comparatively large number of supporting feet 23. Each supporting foot 23 is made up of a rubber plug 24 inserted in a metal cap 25. Embedded in the plug is a nut 26, and a screw 27 passes through the angular portion 22 and threads into the nut 26, to securely hold the supporting feet in position.

28 As will be seen, there are a comparatively large number of these supporting feet thereby providing a substantially uniform radius of stability. In other words, the length of the radius intersecting the discontinuous line connecting the feet is substantially constant throughout the circumference of the base. The plugs 24 may be made of any other suitable material and are preferably givable to some extent in a horizontal direction but to a very little extent in a vertical direction.

40 Secured to the tank bottom 10 is a U-shaped strap 30 having openings in its ends for supporting the driving motor 5. The driving motor may be of any of the well known types, preferably a universal motor running on either direct or alternating current and made very compact. Secured to the casing of the motor is a U-shaped strap 31 having pins 32 and 33 riveted to the ends thereof. The motor 5 is suspended from the upper strap 30 by inserting the pins 32 and 33 in the holes of the upper strap, both from the same side, as disclosed clearly in Fig. 12. A single cotter pin 34 through pin 33 is sufficient to hold the motor in position.

55 The lower strap 31 is insulated from the motor casing. A layer of insulation 35 (Fig. 12) is disposed between the strap and the casing, while surrounding each screw 36 is an insulating bushing 37 and under the head of each screw is an insulating washer 38.

60 The supporting ring 4 is provided with an opening in which a bushing 39 is positioned through which passes the lead wires 42 for driving the motor. Also secured to the supporting ring is a motor switch 43 having its operating lever 44 projecting through on the outside. 65 Mounted on the motor shaft is a pulley 45 having secured to an end face thereof suitable fan blades 46 for blowing a current of air through the motor thereby keeping it cool. The gear box 6 is also provided with a pulley 47 and a drive belt 48 connects the two pulleys for driving the gearing in the gear box. The tension of the belt is regulated by a bolt 49 threaded into a lug 50 on the gear box.

75 The head of this bolt is provided with a re-

cess in which a fibre plug 51 fits for insulating the motor from the gear box at this point. By rotating this adjusting bolt 49 the tension of the belt may be adjusted and a lock nut 52 holds the bolt in adjusted position. Thus it will be seen that by the fibre plug 51 and the insulation 35, 37 and 38 between the strap 31 and the motor casing the motor is entirely insulated from the framework of the machine.

The gear box 6 is made up of a lower main body 53 and a top cover 54 suitably secured together by attaching bolts and nuts 56. The top cover 54 is provided with a plurality of lugs 55 which cooperate with a plurality of lugs 256 on the fitting 11. The lower lugs 55 have recesses 15 in which projections on the upper lugs 256 fit, these recesses and projections being machined to center the gear box on the fitting 11 to obtain proper alignment of bearings for the concentric shafts 57 and 58.

Projecting upwardly from the fitting 11 is a tubular pedestal 59 on which the receptacle 7 is journaled. Disposed within this pedestal are the concentric shafts, an outer tubular shaft 58 and an inner solid shaft 57. The inner shaft 57 is journaled at its lower end in a bearing sleeve 60 disposed in a hub 61 of the casing. To take the end thrust of this shaft an end thrust bearing is provided in the form of a plug 62 threaded into the hub 61 by heavy threads. A lead washer 63 is placed between the hub 61 and the head of the plug 62 and is adapted to be compressed when the plug is tightened sufficiently to obtain proper end clearance for the shaft 57. The threaded connection between plug 35 and hub is made sufficiently strong to stand the necessary force to adjust the plug for proper clearance.

Suitably keyed to the solid shaft 57 is a worm wheel 64 having a slot in its under side in which a pin 65 is disposed, this pin passing through and secured to the solid shaft 57. Resting upon the top surface of the worm wheel 64 is a ball bearing made up of upper race 66, lower race 67 and a holder 68 with balls 69 therebetween. This ball bearing supports the tubular shaft 58 which has keyed thereto a rack pinion 70. This pinion is made up of a tooth segment 71 and a pair of clamping ears 72. A clamp screw 73 passes through one ear 72, is notched into shaft 58, and is threaded into the other ear 72 and a suitable key 74 is provided, to secure pinion 70 on shaft 58. Also secured to the tubular shaft 58 and located over the rack pinion 70 is a flat washer 74 for a purpose hereinafter described. 55 The cover 54 for the gear box is provided with an opening in which a bearing sleeve 75 is disposed to provide a lower bearing for the tubular shaft 58.

For driving the gearing a worm shaft 76 is positioned horizontally on the end of which is suitably keyed the pulley 47. This shaft passes through the walls of the gear box. The gear box is provided with an opening in one side in which is disposed a removable bearing piece 77 secured to the wall of the box by screws. This bearing piece operates as a bearing for one end of the worm shaft 76. The other end of the worm shaft is supported in a bearing 78 integral with the gear box. This shaft supports a first worm 79 meshing the worm wheel 64 and a second worm 80 meshing a second worm wheel 81 for a purpose hereinafter described. The shaft 76 is provided with a thrust collar 82 acting against the removable bearing piece 77 to take up the end 78

thrust. To limit the movement of the shaft 78 the other way a plug 83 is threaded into the casting wall to contact the end of the shaft and a suitable lock nut 84 is provided for holding the 5 plug in adjusted position.

The worm wheel 81 is mounted on an auxiliary shaft 85 journalled in a lower bearing sleeve 86 disposed in a projecting hub 87 of the casing body and an upper bearing sleeve 88 disposed in a 10 projecting hub 89 of the cover. The axial adjustment is obtained by an adjusting arrangement similar to that including the adjusting plug 62 and lead washer 63.

The lower surface of the worm wheel 81 is 15 provided with a groove in which is disposed a pin 90 passing through and fixed to the shaft 85. The worm wheel is provided with a hub 91 and offset projection 92 against which is fitted an eccentric 93. This eccentric has a circular drum 20 portion 94 and a circular flange 95. The eccentric is fitted on the shaft 85 and an auxiliary screw 96 holds the eccentric member and worm wheel together.

Secured to the cover 54 is a rack guide 97 having an opening accommodating a boss 138 (Fig. 10) on the cover 54 and having a guide channel 98 in its lower face. This guide is provided with a pair of openings in which are threaded studs 99 projecting loosely through holes 100 in the cover 30 54. Nuts 130 clamp the guide 97 securely against the cover 54. Sliding in the guide channel 98 is the rack 131 having teeth 132 meshing the teeth 71 on the pinion 70 and having transverse depending ways 133 engaging opposite sides of the 35 drum portion 94 of the eccentric 93, this arrangement forming, in effect, a Scotch yoke. The eccentric flange 95 holds one end of the rack 131 against its guide and the other end of the rack is held against its guide by a bridge member 134 integral with the casing body and having a 40 bronze pin 135 therein to provide a bearing for the rack. An adjusting screw 136 is threaded through a boss on the body wall and engages the side of the rack guide 97. A lock nut 137 locks 45 the screw 136 in adjusted position. It will be understood that the meshing engagement between the rack and pinion may be adjusted by loosening the nuts 130 and 137, adjusting the screw 136 and then tightening the nuts 130 and 137 in adjusted 50 position. The adjusting screw 136 acts as a positive stop to prevent the rack from moving out of engagement with its pinion.

Thus it may be seen that, as the driving motor drives the belt, the gearing in the gear box will 55 drive the tubular shaft, giving it a rotary oscillatory motion and will drive the solid shaft to give it a continuous rotary motion. The use of a Scotch yoke with a rack and pinion drive for the oscillating shaft imparts thereto a motion in 60 which the rates of acceleration and deceleration are equal, and the same in both directions, the stroke being the same in both directions. This expedient has great advantages in assisting in the even distribution of the laundry in the receptacle during washing so that the clothes are 65 evenly distributed for drying. This will be explained more in detail hereinafter.

The upper end of the pedestal 59 is provided with a bearing sleeve 101 (Fig. 4) for the upper 70 end of the tubular shaft 58 and the inside of the tubular shaft has a bearing sleeve 102 for the upper end of the solid shaft 57. Near the lower end of the pedestal 59 there is provided a bearing sleeve 103 having longitudinal grooves to prevent trapping of water inside the hub 107. The upper

end of the pedestal has a conical ring 104 which does not bear against the receptacle hub 107 for either washing or drying but which assists positioning the receptacle on the pedestal when it is replaced after removal for cleaning or other purposes. 5

The receptacle 7 is made up of a side wall 105 having a large number of holes therein so that the receptacle is foraminous, a solid flat, slightly conical bottom 106, a tubular hub 107 and a 10 guard ring 108. These machines may be secured together by simple welded lap joints or by any other common joint used for fastening sheet members together. The joint between the bottom 106 and the hub 107 is reinforced by an angle 15 collar 109. Extending from the hub 107 to the outer wall 105 are a plurality of agitator blades or paddles 8 having large recesses 139. These paddles are suitably secured to the hub 107 and to the outer wall 105 and bottom 106. A spacing 20 collar 110 having notches in which the inner ends of the blades fit is provided for additional strength. These blades not only perform the function of agitation during washing but also act as strengthening braces for strengthening the 25 general construction of the receptacle.

The receptacle is constructed so that the burrs (illustrated in Fig. 13) formed by punching the holes in the side wall 105 face outwardly so that a smooth surface is presented to the laundry in 30 the receptacle. These burrs are ground off by a grind wheel to a certain extent to obviate any possibility of scratching the operator of the machine. The punching operation rounds the inner edges of the holes, thereby insuring a smooth 35 surface on the inside of the receptacle which cannot harm the laundry.

For selectively connecting the receptacle to the drive shafts 57 and 58 a clutch construction is provided. The upper end of the tubular shaft 40 58 is provided with splines 111 and a groove in which a lock ring 112 is sprung. The upper end of the solid shaft 57 has a sleeve 113 pinned thereto, this sleeve having splines 114 of the same radial dimensions as the splines 111. The upper 45 end of the hub 107 is provided with a sleeve-like fitting 115 having splines which selectively engage the splines 111 and 114. This fitting has a recess in which is disposed a ring 116. This ring has secured thereto a push button 117 projecting out through a hole in the sleeve member 115 and in the hub 107. The sleeve member is provided with a second hole in which is disposed a coil spring 118 acting between the ring 116 and the hub 107. A cover 119 having a recess to 55 accommodate the splines 114 fits in the sleeve 115 and is provided with a pair of guides 120 on its lower edge to guide the ring in a direction parallel to the direction of the push button and spring. A suitable locking ring 121 is sprung 60 in a groove in the sleeve to hold the cover in position.

It will be noted that the splines 111 are sufficiently long to be engaged by the ring 116 to hold this ring spaced from the sleeve 113 when the 65 receptacle is in the position illustrated in Fig. 4. This provision obviates wear and the necessity for lubrication between the sleeve 113 and the ring 116 which would occur if these elements touched, since they have different motions. 70

It will be seen that in the position shown in Fig. 4 the receptacle is connected to the tubular shaft for washing and in the position shown in Fig. 5 it is connected to the solid shaft for drying. The tubular shaft 58 is provided with a 75

guard ring 122 overhanging the pedestal to prevent water from accidentally getting down between the tubular shaft 58 and pedestal 59. However, if water does get down between these members it will be seen that it will flow clear of the machine out in the clearance space between the lugs 256 and 55 on the fitting and the gear box as shown in Figs. 1 and 9. A ring 123 of metal or rubber may be secured to the tubular shaft in the clearance space between the fitting 11 and the gear box 6 to further assist in directing the water clear of the machine to prevent such water from getting into the gear box and contaminating the oil therein. The joint 15 between the sleeve 113 on the solid shaft and the tubular shaft is disposed just above the top edge of the tank 1 so that the possibility of water getting down between these shafts and into the gear box is positively prevented.

20 Not only is provision made to prevent water from getting into the gear box but provision is made for preventing oil from the gear box from getting into the clothes space and thereby staining the clothes. The washer 123 in the clearance space between gear box and tank causes any oil which may leak out between the tubular shaft and gear box wall to escape clear of the machine and the joint between the tubular shaft and solid shaft in the gear box is above the level 25 of the oil when the machine is inverted, as for instance during shipment. During use the flat washer 74 secured to the tubular shaft acts as a guard to prevent oil which is squirted or pumped by the meshing teeth on the rack 131 and pinion 10 from escaping between the tubular shaft and casing wall.

From the above it will be seen that, when the clutch and receptacle is in either position, the drive is direct from the drive shaft 57 or 58 to the receptacle without the interposition of loose or movable members. In other words, all parts necessary to secure connection from one of the drive shafts 57 or 58 to the receptacle are either unitary with the drive shaft or with the receptacle. It will also be seen that each of the long concentric drive shafts 57 or 58 is supported in but two radial bearings, an upper bearing 102 for shaft 57 and 101 for shaft 58 and a lower bearing 60 for shaft 57 and 15 for shaft 58, thereby greatly simplifying the fits. Furthermore, it will be seen that the receptacle is journaled on but one bearing 103 located on the pedestal 59 near the bottom thereof and is supported at its other end on the shafts to which it is selectively connected.

Furthermore, it will be seen that all of the gearing necessary for both washing and drying is located in the gear box out of the way, protected from dirt and properly lubricated. This gear box and driving motor are located under the machine within the supporting base ring out of the way and protected from injury. The provision of a relatively large number of supporting feet 23 ensures a substantially constant radius 65 of stability and yet allows the horizontal out of balance forces to be taken up. These feet which are not givable to any extent vertically do not permit tipping the machine to any extent and yet easily take up any small unevenness of the supporting surface and do not mar or scratch the surface. These feet rest directly on the supporting surface and there is no necessity for the machine to be secured thereto, other than by the weight thereof.

70 Furthermore, the machine is small and of

comparatively light weight and therefore can easily be carried from place to place and stored in a small space when not in use. The machine may conveniently be used on a kitchen table or kitchen sink or where water and drainage facilities are available.

To use the machine the drain hose 9 is clipped to its support, thus operating as a valve to prevent escape of the water from the tank. The clutch is set to connect the tubular shaft with the receptacle. The receptacle is filled with the clothes to be washed and the tank filled with water and suitable washing substances. The switch is thrown and the motor will cause the receptacle to oscillate back and forth at a rate which in some cases may be about 78 complete cycles or 156 reversals a minute. The blades or paddles exert an intermittent, centrifugal pump-like action on the water tending to throw the water outwardly. This water then flows upwardly between tank and receptacle back through the upper part of the receptacle and onto the top of the clothes. In addition, the paddles exert agitating action on the clothes and with the water cause tumbling of the clothes, thus exposing all parts of them to the cleansing action of the water.

When it is desired to dry the clothes the hose is unhooked and the water allowed to drain. The receptacle is then lifted to cause connection between it and the solid shaft and the switch is again thrown, this time to drive the receptacle at a constant speed which in some cases may be about 600 revolutions per minute. The rotation of the clothes extracts water therefrom in a well known manner, the water falling to the bottom of the tank and draining out through the hose. The movement of the receptacle during washing, describing the uniformly accelerated and decelerated motion pointed out above, aids in distributing the clothes so that very little trouble is met when drying. The clothes are so evenly distributed during washing that there is practically no vibration during drying and what little there may be is easily absorbed by the rubber feet on the base of the machine.

The immersion of the receptacle and contents during washing imparts a buoying action there to, decreasing the effect of the weight of the receptacle and contents on the thrust bearings which greatly decreases the frictional losses at these points.

Thus a machine is provided which is portable, easily movable from place to place, and has small capacity so that it is not necessary to wait until a large wash is at hand before washing. Furthermore, the machine is reliable in service, easy to operate, and efficient and satisfactory in performance.

While certain novel features of the invention have been shown and described and are pointed out in the annexed claims, it will be understood that various omissions, substitutions and changes in the forms and details of the device illustrated and its operation may be made by those skilled in the art without departing from the spirit of the invention.

What is claimed is:

1. In a laundry machine, a support, a laundry receptacle thereon, agitator members disposed in said receptacle, means for imparting to said members an oscillatory motion in which the rates of acceleration and deceleration are equal and the stroke the same in both directions for washing, and means for imparting to said receptacle a rotary motion for centrifugal extraction, said os- 75

cillatory motion serving to assist materially in the even distribution of clothes in said receptacle so that vibration during centrifugal extraction is minimized.

5 2. In a laundry machine, a laundry receptacle, means for washing laundry in said receptacle by imparting to said receptacle an oscillatory motion in which the rates of acceleration and deceleration are equal and the stroke the same in both directions, and means for drying said laundry by rotating said receptacle at centrifugally discharging speed, said oscillatory motion assisting in the even distribution of laundry in said receptacle to minimize vibration during centrifugal drying.

10 3. In a laundry machine, a tank, a support in said tank, a foraminous laundry receptacle, means for mounting said receptacle on said support for rotary motion, agitator members secured to said receptacle, means for imparting to said receptacle an oscillatory motion in which the rates of acceleration and deceleration are equal and the stroke the same in both directions for washing, and means for imparting to said receptacle a 15 rotary motion for centrifugal extraction, said oscillatory motion serving to assist materially in the even distribution of clothes in said receptacle so that vibration due to centrifugal extraction is minimized.

20 4. In a clothes washing machine, a tank, a clothes receptacle positioned in said tank, said clothes receptacle having an upstanding hub, a hollow pedestal rising from the bottom of said tank, said hub surrounding said pedestal, a plurality of shafts within, said hollow pedestal, a gear box suspended from the bottom of said tank, gearing in said gear box for imparting to one of said shafts a continuous motion for centrifugal extraction, and to another of said shafts an oscillatory, rotary motion in which the rates of acceleration and deceleration are equal and the stroke the same in both directions, clutch means at the 25 top of said hub for selectively connecting the receptacle to said shafts, and agitating blades fixedly mounted in said receptacle for aiding in agitating the clothes.

30 5. In a laundry machine, a tank having an opening in its bottom, a sleeve secured in said opening, a hollow pedestal rising from said sleeve, a gear box comprising a hollow body and a cover, said cover being suspended from said sleeve, a tubular shaft disposed in said gear box and in said pedestal, said shaft having a radial bearing at the upper end of said pedestal and a radial bearing in said cover, an inner shaft in said tubular shaft having a radial bearing at the upper end of said tubular shaft and a radial bearing in the lower part of said body, whereby each shaft has but two radial bearings, a clothes receptacle in said tank and means for imparting washing and drying motions to said receptacle through said shafts respectively.

35 6. In a laundry machine of the class described, a tank, a hollow pedestal in said tank, a gear box secured to said tank, a tubular shaft disposed in said gear box and in said pedestal having a radial bearing near the upper end of said pedestal and a radial bearing near the lower end of said pedestal, an inner shaft in said tubular shaft having a radial bearing near the upper end of said tubular shaft and a radial bearing near the lower part of said box, whereby each shaft has but two radial bearings, a clothes receptacle in 40 said tank and means for imparting washing and

drying motions to said receptacle through said shafts respectively.

7. In a washing machine, a tank, a laundry receptacle journaled in said tank, means for operating said receptacle including concentric shafts, both of said shafts extending above the highest possible liquid level in said tank, a gear box secured to said tank, both of said concentric shafts extending into said gear box to such an extent that, when the machine is inverted, oil in the gear box cannot run down between said concentric shafts, whereby the gear box is protected against water and the washing space is protected against oil.

10 8. In a washing machine, a tank, a hollow pedestal rising from the bottom thereof, a clothes receptacle journaled on said pedestal, concentric shafts in said pedestal, both said shafts extending above the overflow level of said tank, a gear box, means including spaced lugs suspending said box from the tank bottom, said concentric shafts extending into said gear box, a washer secured to said tubular shaft between said tank and gear box to assist water which may leak in between said pedestal and tubular shaft to drain clear of the machine, said concentric shafts extending into said gear box to such an extent that, when the machine is inverted, oil in the gear box cannot run down between said concentric shafts, whereby the gear 15 box is protected against water and the washing space is protected against oil.

20 9. In a machine of the class described, a tank having an opening in its bottom, a fitting secured in said opening, said fitting having spaced depending lugs, a gear box having spaced upstanding lugs disposed opposite said depending lugs, said lugs having interfitting recesses and projections whereby said upstanding lugs are centered with respect to said depending lugs, and means for securing said depending and upstanding lugs together.

25 10. In a portable washing machine of the type which may be lifted from place to place, a tank having an open top for the introduction and removal of clothes, an open top receptacle foraminous at least in its lower portion, agitator members in said receptacle and projecting partially into the clothes space thereof to assist in tumbling the clothes, a gear box containing gearing under said tank for driving said receptacle and agitator members, means for mounting said receptacle and agitator members in said tank for rotation about a vertical axis, selective means connecting said gearing to said receptacle and agitator elements 30 for imparting an oscillatory rotary motion to said agitator members for washing and for imparting a continuous rotary motion to said receptacle for drying, said receptacle being in close proximity to the tank bottom for washing and drying, said receptacle and its contents being immersed in liquid contained in said tank for washing and said tank being drained empty for drying, said tank being just deep enough to hold liquid for the washing operation and to catch 35 liquid discharged from the clothes during the drying operation, said tank having a drain opening in its lower portion and having controllable means for draining the machine, supporting devices located under the tank for supporting the 40 machine on a supporting surface with said gear box in close proximity to the tank bottom and to said supporting surface, whereby the weight of the machine and the head room required is minimized.

11. In a laundry machine, a tank having an opening in its bottom, a fitting having a hub insertable in said opening and a seat engageable with said bottom, a gear box under said bottom, said fitting and gear box having connecting parts, one of said parts having spaced lugs engageable with the other part, and connecting members passing through said connecting parts and said bottom for holding said gear box, fitting and tank in assembled relation.
12. In a laundry machine, a tank having an opening in its bottom, a fitting having a hub insertable in said opening and a seat engageable with the lower surface of said bottom, said fitting having a series of spaced, depending lugs, a gear box having spaced, upstanding lugs disposed opposite said depending lugs, studs threaded into said upstanding lugs and passing through said depending lugs, a collar having holes for said studs and resting on the upper surface of said tank bottom, and nuts threaded on the top of said studs for holding said gear box, fitting and tank in assembled relation. 5 10
